FILING CABINET HANDLE

Charles E. Jones, Chicago, Ill., assignor to Rockwell-Barnes Company, Chicago, Ill., a corporation of Illinois

Application November 6, 1948, Serial No. 58,777

3 Claims. (Cl. 40—8)

1

This invention is concerned with an improved handle for a filing cabinet which handle has incorporated therein a label holder.

The object of the invention is to provide a handle for a filing cabinet which is characterized by a horizontally extending band portion having a relieved section intermediate the ends thereof, the vertical face of the relieved section being slanted rearwardly and upwardly of the vertical face of the band portion and being provided with a bottom ledge formation for supporting a label and a snap-on cover of transparent material adapted to be positioned in the relieved section and to cooperate with the ledge in forming a relatively shallow recess for confining the label therein in fully supported and protected relation.

While the foregoing statement is indicative in a general way of the nature of the invention, other more specific objects and advantages will be apparent to those skilled in the art upon a full understanding of the handle and the label holder which are shown by way of illustration in the accompanying drawings, wherein:

Fig. 1 is a fragmentary perspective view of a filing cabinet equipped with the improved handle;

Fig. 2 is a face view of the handle with the label holding shield removed;

Fig. 3 is a top edge view of the handle likewise with the shield removed;

Fig. 4 is a vertical transverse section taken on the line 4—4 of Fig. 2;

Fig. 5 is a vertical transverse section taken on the line 5—5 of Fig. 2;

Fig. 6 is a view similar to Fig. 5 showing the label holding shield in position; and

Fig. 7 is a perspective view of the shield.

In Figure 1 a handle 10, which incorporates therein the principles of the applicant's invention, is shown applied to the front face of one of the forwardly moving panels 11 of the filing cabinet 12. The panel 11 forms the front wall of a container which either tilts or slides forwardly to give access to the papers or other material filed in the container. The container 11 is elongated horizontally and the handle 10 preferably extends a substantial part of the length of the panel whereby to enable the panel to be opened by grasping the handle at any convenient point throughout its length. The handle 10 is attached to the panel 11 in any suitable manner, as by screws (not shown) which pass forwardly through the back of the panel into concealed apertures 13 in the back of the handle.

The handle 10 is formed of generally T-shaped

2

cross section throughout its length as shown in Fig. 4, being characterized by a vertically disposed finger gripping band portion 14 and by a horizontally disposed web portion 15. The web portion 15 extends from the band portion 14 rearwardly preferably into engagement with the front face of the panel at a point intermediate the upper and lower edges of the band portion. At the ends of the handle the band portion 14 is preferably curved rearwardly at 16 into endwise abutment with the front face of the panel.

The band portion 14 of the handle is provided at one point intermediate its ends, preferably at its center, with a relieved section 17 for the reception of a label holding shield 18. The relieved section 17 is formed so that the vertical face thereof slants rearwardly and upwardly of the bottom edge of the band portion. A relatively narrow rib formation is provided along the bottom edge of the relieved section 17 providing a ledge 19 spaced a short distance from the bottom edge of the band portion. The ledge formation 19 is adapted to support the bottom edge of the label 20 and is of approximately the same depth as the thickness of the label. The top and bottom edges 21 and 22 of the relieved section are offset inwardly of the corresponding edges of the band section, the top edge 21 being also offset rearwardly of the vertical face of the band section due to the slant provided on the front face of the relieved section. A groove 23 is formed in the rear face of the relieved section 17 which extends along the top edge 21 thereof.

The shield 18 is made of a transparent plastic material, and preferably formed by extrusion. The shield 18 is channel-shaped and dimensioned so that it is received in the relieved section 17. The top of the shield 18 is provided with a rearwardly extending flange 24 having a downwardly extending edge 25 which is adapted to seat in the groove 23 of the relieved section 17 when the shield is in position thereof. The bottom edge of the shield 18 is provided with a rearwardly extending flange 26 which terminates in a thickened or beaded edge portion 27. The shield 18 is relatively thin and resilient so that when positioned in the relieved section 17 the beaded edge 27 may be snapped over the bottom edge 22 of the relieved section 17 to hold the shield in position with the lower margin of the front face and the bottom flange 26 thereof substantially flush with the adjoining surfaces of the band portion 14.

The label 20 is first placed with its bottom edge in supporting relation on the ledge 19 after

which the shield 18 is positioned with the rear edge 25 of the top flange 24 seated in the groove 23. The shield 18 is then pivoted downwardly and the bead 27 is forced over the bottom edge 22. The shield snaps into position with the bead 27 engaging the rear edge of the bottom 22 of the relieved section. With the shield 18 in this position the label 20 is firmly gripped between the inner surface of the front wall of the shield 18 and the front face of the relieved section 17 along the top margins of the label. The shield 18 and the ledge 19 cooperate to form with the front face of the relieved section 17 a relatively shallow pocket or recess for receiving the label 20. The vertical edges 28 and 29 of the band portion 14 adjacent the relieved section 17 are curved inwardly and the outer surface of the shield 18 merges at the end edges with the same when the shield is in position in the relieved section. When the shield 18 is in position in the relieved section 17 there are no projecting portions extending beyond the front and top and bottom surfaces of the adjoining band portion which might catch on the clothing of anyone brushing against the handle.

While a preferred embodiment of the invention is presented herein by way of exemplification, it will of course be appreciated that the invention is susceptible of embodiment in other structurally modified forms coming equally within the scope of the appended claims.

I claim:

1. A filing cabinet handle having a horizontally extending band portion, which portion is characterized by a relieved section and by a relatively narrow label supporting ledge within said relieved section and a removable rectangular label retaining shield of relatively thin resilient transparent material encompassing the band portion within the relieved section thereof, said shield being adapted to overlie said ledge and to form therewith a recess for clamping the label therein in a fully supported and fully visible position, said shield having flanged side edge portions engaging the corresponding side edge portions and extending along the back of said band portion at the relieved section thereof to removably retain said shield in position on the handle with the outer face of said shield not extending beyond the plane of the adjacent surfaces of the band portion and merging therewith to provide outer handle surfaces without any obstructions.

2. A filing cabinet handle comprising a horizontally extending band portion provided with a relieved section extending partially around said band portion including the front face and top and bottom edges thereof, the front face of said relieved section being slanted upwardly and rearwardly of the bottom edge of the band, a ledge formation spaced from the bottom edge of said band portion for receiving an index label and a channel-shaped label retaining shield of thin transparent material encompassing said band portion within said relieved section, said shield having reversely extending top and bottom edge portions engaging the top and bottom edges of said relieved section for detachably securing said shield in label clamping position within said relieved section.

3. A filing cabinet handle comprising a horizontally extending band portion of generally rectangular cross section, said band portion having a relatively shallow relieved section intermediate its ends, said relieved section extending along the front face and the top and bottom edges of said band portion providing a label receiving front face inclined relative to the adjacent front face of said band portion, and a resilient covering shield of relatively thin transparent material, said shield being channel-shaped in cross section with the margins of the flanges having reversely extending portions and said shield being adapted to be snapped into position in said relieved section, a relatively narrow label supporting ledge extending along the bottom of said relieved section and forming a relatively shallow label receiving recess between said shield and the inclined front face of said relieved section whereby the label may be positioned in said recess and retained in fully supported and protected relation therein by said covering shield.
